(57) **CLAIM**

The ornamental design for a dual syringe cap, as shown and described.

DESCRIPTION

FIG. 1 is a perspective view of a new design for a dual syringe cap;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof;

FIG. 9 is a bottom perspective view thereof; and,

FIG. 10 is an exploded perspective view, showing the state before the design is coupled to the upper part of a cartridge. The broken lines shown in the drawings illustrate unclaimed portions and form no part of the claimed design.

1 Claim, 11 Drawing Sheets
